UNITED STATES PATENT OFFICE

144,847

DESIGN FOR AN ELECTRIC SADIRON

Gordon W. Florian, Bridgeport, Conn., assignor to
The Winsted Hardware Manufacturing Company,
Winsted, Conn.

Application April 6, 1945, Serial No. 118,873

Term of patent 14 years

(Cl. D49—6)

To all whom it may concern:

Be it known that I, Gordon W. Florian, a citizen of the United States, residing at Bridgeport, in Fairfield County and the State of Connecticut, have invented a new, original, and ornamental Design for an Electric Sadiron, of which the following is a specification, reference being had to the accompanying drawing, forming part thereof.

Fig. 1 is a top plan view of an electric sadiron, showing my new design;

Fig. 2 is a front elevational view thereof; and
Fig. 3 is a side elevational view thereof.

I claim:
The ornamental design for an electric sadiron, substantially as shown.

GORDON W. FLORIAN.
